UNITED STATES PATENT OFFICE.

CLARENCE M. CHAMBERLAIN, OF LEAD, SOUTH DAKOTA.

EXTRACTION VESSEL.

No. 814,940.

Specification of Letters Patent.

Patented March 13, 1906.

Application filed May 31, 1905. Serial No. 268,020.

To all whom it may concern:

Be it known that I, CLARENCE M. CHAMBERLAIN, a citizen of the United States, residing at Lead, in the county of Lawrence 5 and State of South Dakota, have invented certain new and useful Improvements in Extraction Vessels, of which the following is a specification.

This invention is an extraction vessel designed 10 particularly for the treatment of crushed ores, slimes, or other metal-bearing material.

A preferred embodiment of the invention is shown in the accompanying drawings, 15 wherein—

Figure 1 is a perspective view of the vessel with the filter trays and cover removed. Fig. 2 is a transverse section of the vessel, on an enlarged scale, parts being broken away and 20 the filter-trays shown in position. Fig. 3 is a partial horizontal section of one of the trays above the filter-bed. Fig. 4 is a vertical section of the inlet end of a tray. Fig. 5 is a perspective view of a modification. Fig. 6 is a 25 perspective view, on an enlarged scale, of a form of cover for the filling end; and Fig. 7 is a partial vertical section showing a modified construction of tray.

Referring to the drawings, 1 indicates a cylindrical air-tight tank or vessel capable of 30 withstanding internal pressure. The vessel is mounted upon trunnions 2 in suitable bearings and is partially encircled by a reinforcing strap or band 3. The trunnions are preferably located at points between the center of 35 the vessel and the discharge end in order that the horizontal position may be stable. A suitable positively-acting device, here indicated as a pneumatic lift 4, is provided for 40 inclining the tank as required. In the form illustrated in Figs. 1 to 4 a casting 5, secured to the discharge end of the vessel, affords an unobstructed aperture or discharge-gate extending across the vessel through which the 45 filter-trays may be inserted and removed.

A packing 6 is provided on the face of the casting 5, and a similar packing may be provided on the inner face of the cover 7. Rods 8, which preferably pass longitudinally 50 through the tank, project through a central preferably removable bar or section 9 of the casting 5, the projecting portions of the rods 8 being threaded for securing the cover 7. Angle-bars 10 11 or equivalent supporting

devices for the removable filter-trays 12 are 55 secured to the inner walls of the vessel 1.

The filter-trays 12 may be of any suitable size or shape and are conveniently constructed of thin sheet metal having upper marginal inwardly-extending flanges 13 to prevent 60 loss of pulp or solution. By the term "tray" is meant any receptacle of suitable dimensions and capable of use for the collection of the liquid. The bottoms of the trays are doubly reinforced to enable them to withstand 65 without distortion the high pressures which are preferably used for the rapid and economical extraction of ores and slimes. To the under surface of the bottom of each tray are secured a plurality of transverse bars 14 70 in the form of I-beams, as shown in Figs. 2 and 4, or in the form of integral webs 14' on the bottom of a cast-metal tray, as illustrated in Fig. 7. The upper surface of each tray-bottom is provided with a plurality of longitudinal stiffening and supporting ribs 15, 75 preferably formed by closely-placed angle-bars riveted or otherwise secured to the tray. These angle-bars serve also to support the filter-bed. 80

The filter-bed comprises a supporting foraminous sheet 16, shown as consisting of a heavy wire screen resting upon and supported by the angle-bars 15. A filtering layer 17 is supported thereon, and a protective screen or 85 equivalent foraminous sheet 18 overlies the filtering layer. For the screens 16 18 a series of wires or bars, a perforated plate, or other equivalent device may be substituted. The edges of the filter-bed are supported by ribs 90 or projections 19, carried by the trays and are marginally secured from above by bars 20 in such manner as to prevent passage of gas or liquid between the upper and lower frames of the trays otherwise than through 95 the filter-bed. One or more intermediate bars 21 are provided for holding the filter-bed securely in position when pressure is applied from below. 100

The trays are illustrated in Fig. 3 as held in position by threaded bars 22, projecting through the feed end of the vessel 1. When the trays are secured in place, the feed-pipe 23 is brought into operative connection with apertures 24, communicating with the upper compartment of each filter-tray. A pipe 25 is carried by each tray and communicates with the lower compartment thereof, this pipe 105

having external connection through nipples 26, passing through suitable stuffing-boxes on the vessel 1. The discharge end of each tray is unobstructed and is provided with an 5 outwardly-extending flange 27, which when the tray is in position is compressed against the packing 6 on the outer face of the casting 5. Thus the cover 7 constitutes one wall of each filter-tray.

10 The apparatus may be variously modified. Referring to Figs. 5, 6, 7, the vessel 1 is shown as provided with external end flanges 28 29, conveniently of cast-iron. A cast-iron head or closure 30, Fig. 6, on the outer face of 15 which the conduits 23 25 are cast or otherwise secured, is adapted to be bolted to the flange 28, and a cast head 31 is detachably secured to the flange 29. In this construction provision is made for additional trays of appropriate size to be inserted through apertures 32 33. The filter-trays may, if desired, be of cast-iron and may be bolted or otherwise secured to the head 30 to form an air-tight joint therewith, as illustrated in Fig. 7.

20 In the modification shown in Figs. 5, 6, 7, both ends of the several trays are formed by the separable heads of the extraction-tank.

The apparatus is adapted for the treatment of a wide variety of materials, and the 30 nature of this treatment will vary according to the character of the ore and of the solvent. In general the pulp is distributed over the filter-bed and treated thereon with a solvent solution under such conditions of temperature 35 and pressure as may be required. Usually a high pressure is applied above the ore, resulting in a hard and compact cake which cannot be flushed out from the vessel in the usual manner. A cake of this character is readily 40 removed, however, through the discharge end of the filter-tray by tilting the vessel to a position at an angle with the horizontal and then applying a pressure of air or liquid below the filter-bed, whereby the cake is loosened and floated from the vessel. This 45 method of discharging the cake renders necessary the special marginal and intermediate supports and reinforcing devices above the filter-bed, as well as the means for varying 50 the inclination of the vessel.

I claim—

1. An extraction-tank comprising a substantially air-tight vessel, means for inclining the vessel, a filter-bed therein and a discharge-gate extending across the vessel at the end of the filter-bed, substantially as described.

2. An extraction-tank comprising a substantially air-tight vessel, a tray mounted 60 therein, a filter-bed in said tray and a discharge-gate extending across said vessel opposite said tray, substantially as described.

3. An extraction-tank comprising a substantially air-tight vessel, means for inclining 65 the vessel, a tray mounted therein, a fil-

ter-bed in said tray and a discharge-gate extending across said vessel opposite said tray, substantially as described.

4. An extraction-tank comprising a substantially air-tight vessel, a tray mounted 70 therein, a filter-bed in said tray, conduits communicating with said tray above and below said bed and a discharge-gate extending across said vessel opposite said tray, substantially as described.

5. An extraction-tank comprising a substantially air-tight vessel, a plurality of trays mounted therein, a filter-bed in each tray and a discharge-gate extending across said vessel opposite 75 said trays, substantially as described.

6. An extraction-tank comprising a substantially air-tight vessel, means for inclining the vessel, a plurality of trays mounted therein, a filter-bed in each tray, and a discharge- 80 gate extending across said vessel opposite said trays, substantially as described.

7. An extraction-tank comprising a substantially air-tight vessel, a plurality of trays mounted therein, a filter-bed in each tray, 85 conduits communicating with each tray above and below the filter-bed, and a discharge-gate extending across said vessel opposite said trays, substantially as described.

8. An extraction-tank comprising a substantially air-tight vessel, a tray mounted therein, a filter-bed in said tray, a discharge-gate extending across said vessel opposite 90 said tray, and a closure for said discharge-gate constituting one wall of said tray, substantially as described.

9. An extraction-tank comprising a substantially air-tight vessel, a plurality of trays mounted therein, a filter-bed in each tray, a discharge-gate extending across said vessel 95 opposite said trays, and a closure for said discharge-gate constituting one wall of said trays, substantially as described.

10. An extraction-tank, a filter-tray therein having upper and lower compartments 100 separated by a filter-bed, and a support for said bed comprising angle-bars secured to the bottom of the tray, substantially as described.

11. An extraction-tank, a filter-tray therein having upper and lower compartments 105 separated by a filter-bed, a support for said bed comprising angle-bars secured to the bottom of the tray, and reinforcing members below said tray, substantially as described.

12. An extraction-tank, a filter-tray there- 110 in having upper and lower compartments separated by a filter-bed, a support for said bed comprising angle-bars longitudinally secured to the bottom of the tray, and transverse reinforcing members below said tray, 115 substantially as described.

13. An extraction-tank comprising a substantially air-tight vessel, a flange secured to each end thereof, a closure adapted to be secured to one of said flanges, and a filter-bed 120

in said vessel arranged transversely to said closure, said closure having external conduits communicating with the interior of said vessel, substantially as described.

5 14. An extraction-tank comprising a substantially air-tight vessel, a flange secured to each end thereof, a closure adapted to be secured to one of said flanges, and a filter-bed in said vessel arranged transversely to said closure, said closure having external conduits communicating with the interior of said vessel above and below said filter-bed, substantially as described.

10 15. An extraction-tank comprising a substantially air-tight vessel, removable closures for each end of said vessel, and a filter-tray in

said vessel, said closures constituting opposite walls of said filter-tray, substantially as described.

16. An extraction-tank comprising a substantially air-tight vessel, removable closures for each end of said vessel, and a plurality of superposed filter-trays in said vessel, said closures constituting opposite walls of said filter-trays, substantially as described.

20 25 In testimony whereof I affix my signature in presence of two witnesses.

CLARENCE M. CHAMBERLAIN.
